Primary Examiner — Bridget L Eland*(74) Attorney, Agent, or Firm* — Renner, Otto, Boisselle & Sklar, LLP(57) **CLAIM**

The ornamental design for a keypad for a mobile phone, as shown and described.

DESCRIPTION

FIG. 1 is a perspective view of a keypad for a mobile phone showing my design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the remainder of the mobile phone is directed to environment and is for illustrative purposes only; the broken lines form no part of the claimed design.
